UNITED STATES PATENT OFFICE

REINHARDT DAAE, OF YOUNGSTOWN, OHIO

GAS PRODUCER

Application filed May 24, 1924. Serial No. 715,588.

The present invention relates broadly to gas producers, and more particularly to improved means for effecting the desired rotation of the driven parts of a producer.

At the present time it is quite customary to construct gas producers having a rotatable cover and a rotatable base carrying a grate, and interconnect the same for simultaneous operation from a common motor. Due to the heat of the producer, the grit produced, and the location of the driving mechanisms heretofore utilized, effective lubrication has been found to constitute a considerable problem. It is also necessary to rotate the grate at a considerably lower speed than the cover. By the present invention there is provided an efficiently lubricated driving mechanism in which the motor is so located as to be readily accessible and in which the base is driven from a portion of the cover driving mechanism operating at a reduced speed.

In the accompanying drawings there is shown, for purposes of illustration only, a preferred embodiment of the present invention, it being understood that the drawings do not define the limits of the invention, as changes in the construction and operation disclosed therein may be made without departing from the spirit of the invention or scope of my broader claims.

In the drawings:

Figure 1 is a vertical sectional view through one form of gas producer embodying the present invention;

Figure 2 is a top plan view, on an enlarged scale, illustrating a portion of the driving mechanism, and

Figure 3 is a side elevation, partly in section and partly broken away, of a slightly modified form of driving mechanism for the base.

In carrying out the present invention, there may be provided a gas producer body 2 of any usual or standard construction having a cover 3 rotatably supported thereon and an ashpan 4 carrying a grate 5 and mounted for rotation relatively to the body.

The cover is preferably of the type having on its periphery a plurality of teeth 6. Engaging with these teeth for rotating the cov-

er is a spur gear or pinion 7 splined to a short vertical shaft 8. For driving the vertical shaft there is provided a secondary driver 9 preferably in the form of a worm wheel adapted to be driven by the worm 10 secured to the horizontally extending shaft 11. The shaft 11 has secured on one end thereof a gear 12 with which meshes a smaller gear 13 on a second horizontally extending shaft 14. On the other end of this second shaft there is secured a gear 15 with which meshes a pinion 16 on the armature shaft of the motor 17, the motor constituting the primary driver.

The shafts 8, 11 and 14 are preferably carried by bearings formed in a housing 18 within which the worm wheel 9 and the worm 10 are housed. This housing is adapted to be filled with a suitable lubricant up to at least the level of the worm wheel 9, whereby efficient lubrication insuring long life for this portion of the driving mechanism is provided.

It will be apparent that the shaft 11 operates at a speed much lower than that of the motor shaft, and advantage of the speed reducing means for the shaft 11 is utilized in rotating the ashpan 4. This may be accomplished by securing to one end of the shaft 11 a crank or eccentric 19 adapted to cooperate with one end of a pitman 20, the lower end of which cooperates with a lever 21 having an oscillating movement about the axis of a shaft 22. This shaft 22 is journaled in a housing 23 similar in many respects to the housing 18, and carries a worm 24 meshing with a secondary driver in the form of a worm wheel 25 carried by the vertical shaft 26. This shaft also has secured thereto a spur gear or pinion 27 meshing with the annular gear 28 secured to the ashpan 4. The lever 21 preferably carries a pivotally mounted pawl 29 engaging the teeth on the ratchet wheel 30 secured to the shaft 22.

With the construction described, it will be apparent that each rotation of the shaft 11 will be effective for moving the pitman 20 through a complete cycle, thereby moving the ratchet wheel and its associated parts through a distance determined by the angular movement of the lever 21. In order to make the

100

amount of this movement adjustable, the lever 21 is preferably provided with a series of openings 31 with which the pitman may be operatively connected. As the point of connection between the pitman and the lever is moved outwardly from the shaft 22, the amount of movement imparted to the shaft will be lessened, as well understood.

In Figure 3 there is illustrated a slightly modified embodiment of the invention, in which parts corresponding to the parts heretofore referred to in detail are designated by the same reference characters having a prime affixed thereto. In this embodiment of the invention, the lower end of the pitman 20' is pivotally connected to a crosshead 32 which is adjustable along the lever 21' by means of the feed screw 33.

The housing 23, like the housing 18, is adapted to contain a supply of lubricant. Each of these housings and its associated parts represents a complete driving unit which may be bodily removed or replaced, as found necessary. The upper housing, together with the motor 17, is substantially in the plane of the cover 3, thereby rendering it very accessible and bringing it in a zone which is relatively cooler and free from the heavier particles of grit.

The advantages of the present invention arise from the provision of an improved driving means for both the cover and base of a producer.

Further advantages arise from the method of driving the driving mechanism for the ashpan and grate from a portion of the driving mechanism for the cover, which operates at a speed relatively slow as compared to that of the motor speed.

I claim:

1. The combination with a gas producer body, of a cover therefor having a circumferentially extending gear, an ashpan for the producer body having a circumferentially extending gear, a unit driving mechanism for said cover located substantially in the plane thereof, a unit driving mechanism for said ashpan located substantially in the plane thereof, said driving mechanisms each comprising a reservoir for lubricating fluid, and an operative connection between said unit mechanisms, said unit mechanisms being bodily removable from driving relationship with said cover and said ashpan at will.

2. The combination with a gas producer body, of a rotary cover having a circumferentially extending gear and an ash pan having a circumferentially extending gear, of a driving mechanism for said gears comprising a motor disposed in substantially the horizontal plane of said cover, a reduction gear mounted in substantially the same plane, a detachable housing for said reduction gear constituting a reservoir for lubricating fluid in which the reduction gear operates, a reduc-

tion gear for driving the ash pan located in substantially the plane thereof, and connecting means for driving the second named reduction gear from the first named reduction gear, said connecting means comprising a pawl and ratchet, whereby said reduction gears are continuously operated from a single source of power and under conditions of constant lubrication for driving said cover and said ash pan at different speeds and may be readily replaced when desired.

In testimony whereof I have hereunto set my hand.

REINHARDT DAAE.
